UNITED STATES PATENT OFFICE.

PAUL PIERCE, OF CHICAGO, ILLINOIS, ASSIGNOR TO PIERCE WRAPPING MACHINE CO., A CORPORATION OF ILLINOIS.

ADJUSTABLE SUPPORTING MECHANISM.

Application filed November 11, 1922. Serial No. 600,217.

To all whom it may concern:

Be it known that I, PAUL PIERCE, a citizen of the United States, and a resident of the city of Chicago, in the county of Cook and State of Illinois, have invented certain new and useful Improvements in an Adjustable Supporting Mechanism; and I do hereby declare that the following is a full, clear, and exact description of the same, reference being had to the accompanying drawings and to the numerals of reference marked thereon, which form a part of this specification.

This invention relates to an adjustable supporting mechanism for annular articles and particularly to a mechanism which is adapted to be used as a part of a machine which is employed for the purpose of applying a protective wrapping to annular articles such as coils of wire, motor vehicle tires and the like.

The mechanism of this invention is particularly adapted to be applied to a wrapping machine of the type disclosed in U. S. Letters Patent No. 1,399,989, granted to Frank M. Pierce on December 13th, 1921, and I have shown the same in the present application in conjunction with such a machine.

It is an object of this invention to provide an apparatus of the class described whereby an accurate differential adjustment of the annular article relative to the shuttle may be quickly and conveniently made.

It is also an important object of this invention to provide a mechanism of the class described which is adapted to accommodate annuli of varying sectional diameters.

Other and further important objects of the present invention will be apparent from the disclosures in the specification and the accompanying drawings.

The invention (in a preferred form) is illustrated on the drawings and hereinafter more fully described.

On the drawings:

Figure 1 is a side elevation of a wrapping machine for annular articles equipped with the improved supporting mechanism of this invention.

Figure 2 is an enlarged fragmentary elevation, with parts in section, showing the supporting mechanism with a bundle of wire supported thereon.

Figure 3 is a top plan view of the supporting mechanism removed from the wrapping machine.

Figure 4 is an enlarged fragmentary section on the line 4—4 of Figure 1.

Figure 5 is a fragmentary section on the line 5—5 of Figure 4, with parts in elevation.

As shown on the drawings:

The wrapping machine construction to which the improved supporting mechanism of this invention is applied is described in detail in the patent above referred to and therefore need only be described in general terms herein.

The reference numeral 1 indicates a base 70 having a frame member 2 extending upwardly from one end thereof and having spaced brackets 3 extending upwardly from the other end thereof, said frame member and brackets acting to support a shuttle 75 structure 4 which is rotatably mounted on a frame 5 and which has suitable wrapping material applying means mounted thereon.

Journalled in a bearing 6 on the base 1 and in a similar bearing 7 supported on an extension 8 of said base 1 is a drive shaft 9 to which power is transmitted from a suitable source, such as for example an electric motor having a driving pinion meshing with a gear 10 on said drive shaft. The power drive to the drive shaft may be connected or disconnected through a suitable clutch 11 which is operated by a lever 12, and power from said drive shaft is transmitted to the shuttle and wrapping material applying mechanism through a suitable belt 13.

Formed in each of the brackets 3 is an angle slot 14 which communicates with a vertical slot 15 formed in said bracket near the upper end thereof.

The improved adjustable supporting mechanism of this invention which is movably mounted in said angle groove 14 and vertical extension 15 thereof will now be described. Spaced frame plates 16 and 17 are provided, a reinforcing rod 18 being bolted between said frame plates to retain the same rigidly in spaced position. Journalled on said frame plates 16 and 17 near the lower side thereof are rollers 19 which are adapted to be engaged in the slots 14 and 15 formed in the bracket 3, while simi-

lar rollers 20 journaled on shorter shafts extending outwardly from said frame plates near the upper edge thereof, are adapted to be engaged in grooves formed in the 5 inner faces of said brackets 3 in the manner shown and described in the above mentioned patent to Frank M. Pierce.

Also secured between the frame plates 16 and 17 intermediate the ends thereof is a 10 shaft 21 which has a sprocket wheel 22 journaled on each end thereof. Said sprocket wheels 22 are adapted to have sprocket chains 23 engaged thereunder, one end of said sprocket chain 23 being secured to a 15 bracket 3 as indicated at 24 and the other end of each of said sprocket chains 23 extending upwardly over an idler sprocket 25 journaled on a stub shaft extending outwardly from the bracket 3 and thence to 20 a drum 26 mounted on a shaft 27 which is journaled on the frame member 2 and which is adapted to be rotated by a worm and worm gear mechanism 28—29 which is 25 operated by a handle 30. Thus, by rotation of the handle 30, it is possible to raise and lower the frame plates and mechanisms supported thereon relative to the brackets 3, the rollers 19 and 20 moving in the slots 14 and 15 and in the grooves provided in 30 said bracket 3.

Journalled between one end of the frame plates 16 and 17 at a point near the upper edge thereof, is a shaft 31 which is driven from a sprocket 32 mounted on the end 35 thereof outside the frame plate 17 in a manner to be described hereinafter. Secured to said shaft 31 intermediate the frame plates 16 and 17 is a drum or flanged pulley 33, the outer surface of which is corrugated as indicated at 34 to aid in imparting 40 a rotational drive to a coil of wire or other annular article 35 supported thereon.

In order that annular articles of varying 45 sectional diameters may be held firmly in association with the drum or pulley 33, adjustable flange structures for said pulley are provided which will now be described. Said structures each comprises a hub 36 which is slidably mounted on the shaft 31 50 just inside the frame plates 16 and 17, and integral with each of said hubs 36 is an outwardly extending annular plate 37. Said plates 37 are provided with a plurality of 55 apertures adapted to have pins 38 secured therein, said pins 38 extending inwardly in opposite directions into passages 39 formed in the web of the drum or pulley 33. The pins 38 are slideable in the passages 39 and 60 in view of the fact that the same are secured to the plates 37 a drive is imparted from the pulleys 33 to said plates 37 and hubs 36 irrespective of the position of said hubs relative to the shaft 31.

Integral with and extending outwardly 65 from the plates 37 are extensions 40 having

recesses therein which are adapted to permit said extensions to be slid over the flange on the pulley or drum 33, and said extensions 40 are provided on their inner faces with integral inclined flange portions 42 70 that are adapted to support the annular article in position on the drum or pulley 33.

The mechanism whereby an inward and outward movement of the hubs 36 and the inclined flanges 42 supported thereon is 75 effected will now be described. Pivotally mounted between the frame plates 16 and 17, on blocks 43 and 44 which are secured to the frame 1 adjacent the inner sides of said frame plates near the lower edge 80 thereof, are levers 45 and 46 which are provided at their lower ends with integral inwardly extending arms 47 and 48 respectively. The inner ends of said arms 47 and 48 are joined together by a pivotal connection 49 of the type shown in Figure 5, the pivot pin 50 extending from said pivotal connection outwardly through an angle slot 51 formed in a plate or bar 52, said bar 52 also having slots 53 and 54 therein through 85 which extend pivot pins 55 and 56, used to pivot the levers 45 and 46 on the slots 43 and 44. Said slots 51, 53 and 54 are of such width that the plate 52 is freely movable relative to the pins 50, 55 and 56, and 90 the plate is held from outward movement away from said pins by suitable washer and cotter keys engaging over the outer end of the pins in the manner shown in Figures 4 and 5. Means are provided for moving the plate 52 longitudinally so that longitudinal movement imparted thereto will cause a movement of the pivot 49 due to the movement of the pin 50 in the angle 95 slots 51, this movement of the pivot 49 100 causing a consequent movement of the upper end of the levers 45 and 46 toward or away from each other. The movement of said plate 52 is accomplished by means of a lever 57 which is pivoted on the frame plate 16 at 58 and which has depending from the pivot point thereof an integral crank arm 59 which is pivotally connected at 60 to the end of said plate 52. The upper ends of the levers 45 and 46 have forks 61 formed thereon which engage around collars 62 rotatably mounted on the hub 36 and abutting shoulders formed on said hub, said collars 62 preferably being secured in 105 position from longitudinal movement relative to the hub by locking collar 63 pinned to the hub outside said rotatably mounted collars 62. Each arm of the forked portions on the levers 45 and 46 is again bifurcated in a plane perpendicular to the plane of the forked portion 61, said bifurcated portion being engaged over oppositely positioned trunnions 64 extending outwardly 110 from the collars 62.

Although considerable adjustment of the 115

supporting mechanism is afforded by the movement thereof in the grooves 14 and 15 formed in the brackets 3, it is often desirable that an additional adjustment be provided 5 in order that a machine on which the supporting mechanism is mounted may accommodate annular articles throughout a large variety of diameters, and in order that each of said annular articles may be properly positioned 10 with reference to the rotatable shuttle to assure the correct application of wrapping material 65 to the annular article 35. This adjustment is obtained through a supporting roll or pulley 66 which has a 15 concave article supporting surface and which is secured to a shaft 67 journaled in bearings 68 and 69 supported on separated arms 70 and 71 extending upwardly from a sleeve 72 pivotally mounted between the 20 frame plates 16 and 17 near the lower edge thereof and at the end opposite the drum 63. A sprocket 73 is secured to the outer end of said shaft 67 in alignment with the sprocket 32 and a drive is imparted to said 25 sprockets and consequently to the supporting means for the annular article through a sprocket chain 64 which engages a sprocket 75 driven through suitable connections from the drive shaft 9. Said sprocket chain 74 30 passes over a suitable idler sprocket 76 mounted on the base 1 and under an adjustable idler sprocket 77 journaled on a chain adjusting pivotally mounted weight 76.

A lever 79 which is pivotally mounted 35 on the frame plate 16 at 80 and which is adapted to be held in adjusted position by the engagement of a usual spring-pressed pawl 81 thereon in a notched segment 82 secured to the frame plate 16, is provided 40 for rotating the sleeve 72 and consequently differentially adjusting the supporting roll 66. A connection between said lever 79 and the sleeve 72 is afforded by an integral crank arm 83 extending inwardly from one 45 end of said sleeve 72, the outer end of said crank arm being pivotally connected to a pair of parallel links 84 engaged on either side thereof and extending upwardly to either side of the lever 79 where they are 50 connected to said lever intermediate the ends thereof by a pivotal connection 85.

It is apparent that by the provision of the connections just described, a downward movement of the lever 79 is adapted to effect 55 an upward and inward movement of the supporting roller 66, thus accommodating the supporting mechanism to annular articles of smaller diameter while an upward movement of the lever 79 permits a downward and outward movement of said supporting roll 66 accommodating the supporting mechanism to annular articles of larger diameter.

The operation and action of the mechanism of this invention will be apparent from

the foregoing description, the mechanism being particularly provided to adapt a wrapping machine of the class described for use in wrapping a large variety of annular articles of varying diameters and of varying 70 sectional diameters. The adjustment of the mechanism for articles of varying sectional diameters is of course effected by manipulation of the lever 57 which causes the hub 36 and consequently the flange members 42 to 75 be moved inwardly or outwardly to properly contact the sides of the annular article, while manipulation of the lever 79 effects a differential inward and upward or downward and outward movement of the supporting roll 80 66 to properly position the annular article relative to the shuttle.

The supporting mechanism of this invention has been shown and described in connection with a particular wrapping machine, 85 but it is apparent that the principles of adjustment and the mechanism for effecting such adjustment may be employed in a large variety of machines used for this purpose.

I am aware that numerous details of construction may be varied through a wide range without departing from the principles of this invention, and I therefore do not purpose limiting the patent granted hereon otherwise than necessitated by the prior art. 95

I claim as my invention:

1. In a mechanism of the class described, rotatable supporting means, and means on said supporting means, simultaneously and positively movable to contact and centrally 100 position supported articles of different sizes.

2. In a mechanism of the class described, rotatable supporting means, flanges for said supporting means axially movable relative thereto, and means for moving said flanges 105 equal amounts in opposite directions into a desired adjusted position.

3. In a mechanism of the class described, rotatable supporting means, flanges for said supporting means axially movable relative 110 thereto, and means for simultaneously positively moving said flanges in opposite directions.

4. In a mechanism of the class described, rotatable supporting means, flanges for said supporting means axially movable relative thereto, and pivotally mounted means for 115 positively moving both of said flanges into a desired adjusted position.

5. In a mechanism of the class described, rotatable supporting means, flanges axially 120 adjustable relative to said supporting means, and a toggle mechanism for positively moving said flanges into desired adjusted central position.

6. In a mechanism of the class described, a plurality of rotatable supporting means for annular articles, certain of said supporting means being adjustable to centrally position annular articles of different diameters 130

and certain thereof being adjustable to properly position annular articles of different sectional diameters.

7. In a mechanism of the class described, 5 a frame, rotatable supporting means thereon, means for adjusting said supporting means relative to the frame and secondary adjusting means for moving said supporting means simultaneously towards or away from each 10 other.

8. In a machine of the class described, 15 a work support comprising a plurality of rotatable rollers adapted to support and turn the work placed thereon, said rollers having longitudinally slideable collars mounted thereon, and means for positively and simultaneously moving said collars an equal amount in opposite directions respectively.

20 9. In a machine of the class described, a work support comprising a plurality of rotatable rollers for supporting and turning

the work, adjustable, longitudinally slideable collars on said rollers, and means for simultaneously moving said collars an equal 25 amount in opposite directions respectively longitudinally of said rollers and for holding the same in adjusted position.

10. In a machine of the class described, 30 rotatable rollers for supporting the work to be wrapped, longitudinally slideable collars on said rollers, cooperating bell cranks for adjusting said collars, said bell cranks being connected for simultaneous and equal movement in opposite directions and a lever for 35 operating said bell cranks to move said collars toward and from each other.

In testimony whereof I have hereunto subscribed my name in the presence of two subscribing witnesses.

PAUL PIERCE.
